UNITED STATES PATENT OFFICE.

GALEN W. PEARSONS, OF KANSAS CITY, MISSOURI.

MACHINE FOR LINING WATER OR OTHER PIPES.

SPECIFICATION forming part of Letters Patent No. 274,138, dated March 20, 1883.

Application filed November 10, 1882. (No model.)

To all whom it may concern:

Be it known that I, GALEN W. PEARSONS, a citizen of the United States, residing at Kansas City, in the county of Jackson and State 5 of Missouri, have invented a new and useful machine for lining the interior of water or other pipes with asphaltum or other similar material when the same is made liquid or plastic by heat; and the object of my improvement 10 is to line such pipes with such material in any desired thickness and with uniform caliber at a single operation. I attain these objects by the mechanism illustrated in the accompanying drawings, in which—

15 Figure 1 is a vertical elevation, broken to show indefinite height; Fig. 2, a plan of the top of the machine, and Fig. 3 a plan of the bottom after the removal of the pipe.

Similar letters refer to similar parts throughout the several views.

The box A A and the posts B B B B constitute the frame-work of the machine. In the top of the box is an opening corresponding in the size of its lining O O to the finished interior diameter of the pipe. The lining O O is elastic, being slightly drawn back by the screws p p p p, working in the nuts Q Q Q Q, or their equivalent, to allow the insertion of the plunger-guide H, and afterward adjusted 25 to it. The guard H, which is attached to the plunger G, is made of canvas or other textile material kept in form by coiled wire or other equivalent device. The plunger G is of wood or hollow metal, so as not to cool the melted 30 material resting upon it. It is provided with guides I to keep it central.

O C is the pipe.

D D is a spout attached to a frame, E E E, sliding upon the posts B B B B, the spout 40 forming a guide to the top of the pipe, and also, by the raised guard F, a guide to the lifting-rod K, the spout being for the purpose of carrying off surplus material, and for the purpose of preventing accumulation of such material by cooling may be heated by steam or otherwise, as most convenient. The rod K fastens to the plunger-guide I by a clutch. When raised to the top of the pipe the guide, 45 striking the guard F, lifts the spout and frame off the pipe, thus permitting its removal.

N is a water-pipe entering the box A A. It

is continued by a hose hung to the plunger G for the purpose of maintaining a circulation of cool water in the upper part of the pipe C C as the plunger G rises.

M is a flexible hose, permitting the water to obtain a uniform pressure upon the bottom of the plunger G. The end of this hose is attached to the cross-bar L of the rod K and rises with it, either by water-pressure alone or 55 in part, as may be desired.

The action of the device is as follows: The plunger G being placed in the position shown in the drawings, the pipe C is placed in position, the upper frame and spout being lowered 60 upon it, holding it down and in place. The rod K is now lowered, and, engaging with the plunger-guide I, is ready for lifting the plunger G, with its follower H. Molten asphaltum or other material in sufficient quantity to line 65 the pipe is now poured into it, the box A A being full of water, between which and the molten material the flexible ring O O forms a partition. Water being now admitted by the pipe N, overflows through the hose M, as the 70 plunger G and its guard H are lifted in whole or in part by its pressure. The molten material flowing outside of the plunger G is held in place by the guard H, which, being of textile material and wet, does not adhere to it, 75 but cools it sufficiently to keep it in place, the water rising and filling the pipe, completing the cooling process. When the plunger reaches the top of the pipe the surplus material flows off by the spout D, and its further rise, lifting 80 the spout and its frame-work, permits water to overflow the pipe without coming in contact with the molten material and releases the pipe for repetition of the process with others.

I am aware that the lining of pipe with plastic material is common, and that a plunger similar to the plunger G is used for the purpose. I therefore make no claim to the plunger G. Neither do I claim the particular shape or arrangement of parts of the machine.

What I claim as my invention, and desire to secure by Letters Patent, is—

1. The method herein described of lining pipes with a material which will harden when cold, the same consisting in applying the material to the inside of the pipe, with a former or plunger working inside of said pipe, and

following said former or plunger with a column of water or other cooling material, as set forth.

2. The method herein described of lining water-pipes with bitumen, the same consisting in applying the bitumen in a fluid condition and immediately cooling the same.

3. The combination of the former or plunger G with the guard H, whereby the material is applied to the interior of the pipe and smoothed and set thereon, as set forth.

4. The combination of the former or plunger G, provided with the guard H, with the pipe C, box A, and water-supply pipe N.

5. The combination of the pipe C, plunger G, and hopper I, whereby the material is gathered and saved, as set forth. 15
